(57) **CLAIM**

The ornamental design for a package with transaction card, as shown and described.

DESCRIPTION

FIG. 1 is a front, perspective view of a package with transaction card showing a first embodiment of our new design; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines are portions of or environmental subject matter to the package with transaction card and form no part of the claimed design. The bolded short dash-long dash lines indicate the bounds of the claimed subject matter and otherwise form no part of the claimed design.
